[57] CLAIM

The ornamental design for a garment display stand, as shown and described.

DESCRIPTION

FIG. 1 is a perspective view of a garment display stand showing my new design; the right and left sides being mirror images of that shown;

FIG. 2 is a perspective view similar to FIG. 1 with the garment holders removed from convenience of illustration;
and

FIG. 3 is a perspective view of a modified form of the stand shown in FIG. 2.
